UNITED STATES PATENT OFFICE.

MOSES Z. VIAU, OF MALONE, NEW YORK.

PIPE-WRENCH.

SPECIFICATION forming part of Letters Patent No. 668,467, dated February 19, 1901.

Application filed November 19, 1900. Serial No. 36,984. (No model.)

To all whom it may concern:

Be it known that I, MOSES Z. VIAU, a citizen of the United States, and a resident of Malone, in the county of Franklin and State 5 of New York, have invented a new and Improved Pipe-Wrench, of which the following is a full, clear, and exact description.

This invention relates to a pipe-wrench of that class in which a jaw is pivotally mounted on a hand-lever, the parts being arranged to engage the pipe in various positions of the jaw with respect to the lever.

The object of the invention is to simplify and strengthen the construction of these parts 15 and at the same time to provide a wrench which may be engaged with the pipe in a great number of different positions, and which also will automatically adapt itself to pipes of greatly-varying sizes.

20 This specification is a specific description of one form of the invention, while the claims are definitions of the actual scope thereof.

Reference is to be had to the accompanying drawings, forming a part of this specification, 25 in which similar characters of reference indicate corresponding parts in all the views.

Figure 1 is a perspective view of the invention, showing it engaged with a pipe. Fig. 2 is a longitudinal section taken in the flat plane 30 of the wrench. Fig. 3 is a detail perspective view of the hardened jaw-face, and Fig. 4 is a view showing the pipe in a second position.

a represents the handle of a wrench, the working end of which has a fork-like construction producing two arms *a'*, such arms standing at an acute angle to each other and being serrated around both their inner and outer edges. The jaw or movable member, which is pivoted on the handle *a* just below 35 the arms *a'*, comprises two cheek-pieces *b*, rigidly connected together by a preferably integral web *b'*. (See Fig. 2.)

*b*² represents the working face of the movable jaw, and this may, as shown in Fig. 3, be formed separate from the jaw proper and removably fastened thereto, as shown in the drawings. The advantage of this construction is that the working face of the jaw may then be constructed of hardened tool-steel, 45 while the other parts of the jaw may be formed

of a cheaper metal. The movable jaw has a transverse passage *b*³ formed therein, through which the jaw may be passed.

The web *b'* is so arranged that it clears the ends of the arms *a'* of the handle *a*, permitting the movable jaw to swing freely from one side of the handle to the other. This is also true of the working face *b*² of the jaw. This construction enables me to place the working jaw in a great number of positions, 55 in each of which it will be capable of gripping a pipe.

In using the wrench the pipe may be passed through the opening *b*³ of the movable jaw and made to assume either one of the four 60 following positions—namely, against the inner side of either one of the arms *a'* and against the outer side of either one of said arms. Further, the pipe may be engaged between the working face *b*² of the movable jaw 65 and the arms *b'* at either of the two following positions: at the inner side edge of one of the arms *a'* (see Fig. 4) and at the outer side edge of the arm *a'*, which is shown uppermost in Figs. 2 and 4. It will therefore be seen that 70 the pipe may be taken in any one of six positions of the movable jaw without reversing the jaw. The jaw may be reversed on the hand-lever, if desired, and, indeed, it may be used in various other ways which will suggest 75 themselves to a skilled mechanic. It is also apparent that the wrench will automatically adjust itself to the size of the pipe. But one hand of the user is necessary to operate the wrench, since by passing the pipe through 80 the opening *b*³ the pipe may be gripped by simply turning the wrench to one side or the other. Also, owing to the shape of the working face of the movable jaw, the wrench may be readily engaged with a pipe which is laid 85 flat against a wall or floor.

Having thus described my invention, I claim as new and desire to secure by Letters Patent—

1. A pipe-wrench having a handle, one end 95 of which is in the form of a fork, producing two arms thereat, and a movable jaw mounted on the handle intermediate the arms and having a transverse opening therein for the reception of a pipe. 100

2. A pipe-wrench having a handle, one end of which is in the form of a fork, producing two arms, and a movable jaw mounted on the handle and having a transverse opening for the reception of a pipe and also having a working face transversely projected from the jaw.

3. A pipe-wrench having a handle with one end forming a stationary jaw, and a movable jaw mounted on said end of the handle and having a transverse opening for the reception

of a pipe, and also having a laterally-projected portion forming a working surface or jaw.

In testimony whereof I have signed my name to this specification in the presence of two subscribing witnesses.

MOSES Z. VIAU.
